CLAIM

The ornamental design for a combined sleep position pillow and aid for preventing snoring, as shown and described.

DESCRIPTION

FIG. 1 is a top plan view of a combined sleep position pillow and aid for preventing snoring showing my new design;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a right side elevational view thereof; and

FIG. 7 is an enlarged, fragmentary vertical cross-sectional view thereof, taken along line 7—7 of FIG. 1.

FIG. 1

FIG. 2

FIG. 3

FIG. 4

FIG. 5

FIG. 6

FIG. 7
